UNITED STATES PATENT OFFICE.

EDWARD E. CLEMENT, OF WASHINGTON, DISTRICT OF COLUMBIA, ASSIGNEE, BY
MESM ASSIGNMENTS, TO FREDERICK C. STEVENS, OF ATTICA, NEW YORK.

TELEPHONE-EXCHANGE SYSTEM.

1,107,157.

Specification of Letters Patent. Patented Aug. 11, 1914.

Application filed September 12, 1905, Serial No. 378,848. Renewed March 18, 1912. Serial No. 755,526.

To all whom it may concern:

Be it known that I, Edward E. Clement, a citizen of the United States, residing at Washington, in the District of Columbia, have invented a certain new and useful Improvement in Telephone-Exchange Systems, of which the following is a specification, reference being had therein to the accompanying drawing.

10 My invention relates to telephone exchange systems, and has for its object the provision of means for automatically ringing a wanted subscriber, and ceasing so to ring when the subscriber answers.

15 Briefly stated, my invention comprises a ringing relay of very high resistance relatively to the line-circuits, which is connected with a line upon connecting therewith by a calling link terminal, and is thereafter energized at intervals by means of a suitable commutator so as to put the ringing generator to line. When the subscriber answers he closes the line-circuit to form a shunt of relatively low resistance about the 20 ringing relay. The ringing relay may continue to hold up until the commutator has terminated the period in which it happens to be, but after a relay circuit is once broken by the commutator, it will not again pull up by reason of the insufficiency of the current which it receives.

25 My invention is hereinafter described as applied to a two-wire multiple common battery manual exchange, but it is equally applicable to any other type of system or exchange employing link circuits of any character, with terminals for switching and interconnecting the lines together. Therefore I do not wish to be limited to a manual system, nor to the particular type of system herein described and illustrated.

30 The invention is illustrated in the accompanying drawing, in which the figure is a diagram showing two subscribers' stations and a central station, with line and cord-circuits for purposes of interconnection.

35 In the drawing, A is one sub-station, and A' another, each equipped with a transmitter, receiver, switch-hook, ringer, and condenser, as usual in common battery systems. From the sub-station, line-wires 1 and 2 extend to the central office, where they terminate upon contacts n, n' of the cut-off relay N, normally connected through wires 5 and 6 to the line-relay M and battery B, and to

the ground, respectively. When the cut-off relay is energized the line-wires are extended through the branches 3-4 to the jacks J. The line-relay M controls a local circuit containing a signal lamp m, associated so with one of the jacks, J, known as the answering-jack.

40 The interconnection of the lines shown is accomplished by means of the cord-circuit, 7, 8, 9, 10, having an answering-plug P and a calling-plug P'. The cord is inductively separated by condensers C into answering and calling ends, and for the purpose of supplying battery current for the transmitters and signals during connection, 45 the battery B is bridged across both ends of the cord-circuit, the answering end through the bridge-wires 11 and 12 and the calling end through the bridge-wires 13 and 14. The wire 11 contains the supervisory relay S, the 50 wire 12, the supervisory control relay S², the wire 13 the supervisory relay S', and the wire 14 the supervisory control relay S³. The relays S, S², jointly control the local circuit of the supervisory lamp s, while the 55 relays S' and S³ similarly control the lamp s'. The lamp s, being associated with the answering plug P, responds to the calling subscriber's circuit changes, while the lamp s' being associated with the calling plug P' 60 responds to the acts of the called subscriber.

65 So far the apparatus and circuits I have described are of well-known construction, and I do not claim any of their features as my invention. The invention resides particularly, however, in the parts I am now about to describe. For the purpose of communicating and testing, the operator is supposed to have a listening key, as usual, but she has no ringing key, the relay R 65 taking the place of this key. The winding of the relay is connected on one side to a commutator R' through the wire 18, and on the other side through the wire 20 to a front contact on the relay S³. 70 This relay is connected between the battery wire 15 and the cord-conductor 10 passing to the sleeve of the calling plug P'. It has two armatures s³ and s³⁰, the first of which connects the battery wire 15 by wires 16 and 19 to the armature s¹⁰ of the relay S'. This is the supervisory relay of the calling plug. The other armature s³⁰ of the relay S³ when attracted closes a branch 17-20 from the 75 wire 14 to the relay R, which is therefore 80 85 90 95 100 105 110

also connected to the cord-conductor 10 when the plug P' is inserted in a jack J'.

The relay R has a pair of armature contacts r, r' , which are normally closed upon 5 back contacts r^2 and r^3 to maintain the continuity of the cord-conductors 9 and 10. When the relay is effectively energized, however, the armatures r and r' are drawn in to break away from the contacts r^2 and r^3 and 10 close upon the contacts r^4 and r^5 , which form the terminals of a local circuit, including the ringing generator G. In other words, the relay acts just as a ringing key would, severing the cord-circuit and connecting the 15 calling plug to the generator. The sleeve side of the generator circuit is connected through a suitable resistance r^6 to the battery wire 15, in order that while ringing, the cut-off relay N' will be held up with- 20 out chattering.

The operation of my system thus described is as follows: Subscriber A takes down his receiver, and lamp m lights. The operator inserts answering-plug P, relays N, 25 S² and S become energized, lamp m is extinguished and line-wires are connected through the cord to the operator's telephone, not shown. Having ascertained the number wanted, the operator tests the jack J' with 30 the tip of the plug P', and finding the line idle inserts the plug. Relays N' and S³ are at once energized, the line is completed from substation A' to the cord-conductors 9--10, and the lamp s' glows. Relay S³ having 35 completed the circuit from the battery wire 15 through its own windings to the wire 17 and through 20 to the relay R, the commutator R', which is constantly revolving, takes control of the relay, for after each one of 40 its revolutions it grounds the relay through the wire 18, leaving it ungrounded during the other half revolution. While I speak of this as a half revolution in each case, it will be understood that it may be anything 45 desired. If the commutator is timed to make one complete revolution in eight seconds, and so divided equally as shown, the relay R would be energized for four seconds and deenergized for four seconds, attracting 50 its armatures, r, r' , when energized to throw ringing current on the wanted line and so out to the substation A'. Any number of variations can be made in the order and arrangement of the ringing intervals, without 55 departing from my invention. When the subscriber answers, if the circuit 18 is at the moment broken at the commutator the relay R will be deenergized, and when the commutator again closes the circuit it will not be- 60 come effectively energized by reason of the shunt circuit established around it through the line as follows: 14, 10, P', J', 1, A', 2, J', P', (tip), 9, S', ground. The resistance of this line-circuit, from the wire 14 to 65 ground and including the relay S' and the

talking set at the substation, may vary from about 150 ohms to 300. Under ordinary conditions, in a well designed system, the maximum will not exceed 250 ohms. I make the windings of the relay R high, by 70 preference, 1,000 ohms being a satisfactory resistance. The current supply passing through the 100 ohm relay S³ divides between the relays R and N' until the subscriber answers, and after that the larger 75 part of the current flow passes to line, the proportion passing through the relay R being too small to energize it so as to hold up its armatures. Hence the ringing stops.

A number of differences may be observed 80 between my system and those heretofore proposed. In some cases a relay has been employed to connect the ringing generator to line, leaving it so connected until the called subscriber answers, when the consequent 85 rush of current works another relay or magnet to remove the generator from the line. As distinguished from this, it will be perceived that my generator is not directly connected to the line by the act of the operator, 90 but that a ringing mechanism is so connected, which is thereafter controlled mechanically by means of the commutator. The generator is in no sense removed from the line by the act of the subscriber, nor is the 95 ringing mechanism disconnected. In fact the latter remains connected throughout the conversation, being merely disabled as long as the line-circuit continues closed. I can, however, provide means for disabling the 100 relay R' permanently after the subscriber has answered, this for the purpose of preventing generator current being thrown again upon his line to call him back to the 105 telephone after he has finally hung up the receiver. For this purpose I provide a shunt about the relay R controlled by the self-locking relay R², whose windings are grounded on one side and connected by wire 21 to a front contact on the relay S'. When 110 the called subscriber answers the relay S' pulls up to extinguish the lamp s' and at the same time closes the circuit 15, 16, 19, 21 to relay R². The relay R² then pulls up, locking itself through the short-circuit 19--22, 115 and at the same time closing the permanent shunt 23--24 about the relay R. The relay R² will continue to hold up even after the subscriber A' has opened his line, and the relay R will therefore continue to be dis- 120 abled, until plug P' is pulled.

I have shown only one generator at G, but it will be obvious that the invention may be applied to party-line systems employing any desired arrangement, such for example 125 as shown in Letters Patent No. 779,533 granted to William W. Dean January 10, 1905.

Having thus described my invention, what I claim and desire to secure by Letters Patent is:

1. In a telephone exchange system, subscribers' stations having ringers, a central station, and line circuits interconnecting the same, connecting apparatus for the lines and 5 a ringing generator at the central station, a relay and circuit connections therefor becoming partially operative when connection is effected with a line, a periodic circuit closer acting to render the circuit and relay 10 completely operative at intervals to put the ringing generator current to line, and a relatively low resistance shunt about the relay closed when the subscriber answers.
2. In a telephone exchange system, the 15 combination with subscribers' lines and signals, of central office connecting apparatus, a source of signaling current, switching means to connect said source to a subscriber's line, means for intermittently actuating the switching means, and means controlled by the subscriber to place a rela-
- 25

tively low resistance shunt about the switching means, thereby disabling said switching means during the continuance of the connection.

3. In a telephone exchange system, the combination with subscribers' lines and signals, of the central office connective apparatus, a source of signaling current, switching means to connect said source to a subscriber's line, a commutator controlling said switching means at intervals, and means controlled by the subscriber to close his line so as to form a relatively low resistance shunt about the switching means to disable the same between intervals.

In testimony whereof I have affixed my signature in presence of two witnesses.

EDWARD E. CLEMENT.
